JOHN J. TURNER, OF BATAVIA, NEW YORK, ASSIGNEE TO UNIVERSAL GYPSUM & LIME CO., OF CHICAGO, ILLINOIS, A CORPORATION OF DELAWARE.

METHOD OF AND APPARATUS FOR CUTTING PLASTER BOARD OR ANALOGOUS MATERIALS.

Application filed May 28, 1923. Serial No. 641,927.

This invention relates to methods for cutting plaster board or analogous materials and to a knife for use in connection with the method of cutting.

- 5 In the manufacture of plaster board, plaster in semiliquid or plastic condition is fed between two sheets of paper or other fibrous material and is passed through machinery for forming the board, the board being in a
 10 substantially endless strip or sheet. After the board has been completely formed and while the core is still only partially dried and hardened, the board is cut into lengths that can be easily handled and the drying and the
 15 hardening of the plaster core are completed after the cutting operation. While the board is in this soft or plastic condition, great care must be taken that the paper is not torn from the core by the knife, since otherwise the edge
 20 portion of the board will be defective and not usable to the best advantage in building construction. Owing to the softness of the core, the difficulty presents itself that if a guillotine cutter comprising a knife of ordinary
 25 construction is used, the core will be squeezed by the knife due to the fact that the paper covering is tough and very much harder to cut than the soft core, so that the edges of the board will not be of uniform thickness.
 30 The objects of this invention are to provide a method of cutting plaster board in such a manner that the paper will not be loosened from the core, and so that the soft core will not be squeezed out or otherwise damaged by
 35 the pressure exerted thereon by the cutting knives; also to provide a cutting knife of improved construction for use in severing plaster board while the core thereof is in soft or plastic condition; also to improve methods
 40 of this kind, and knives for cutting plaster board in the other respect hereinafter specified.

In the accompanying drawings:

- Fig. 1 is a fragmentary transverse section 45 of a strip of plaster board passing through the forming machinery and showing the same in operative relation to the knives embodying this invention, parts only of the knives being shown in elevation.
 50 Figs. 2 and 3 are similar fragmentary views showing the knives in different positions with reference to the board, Fig. 2 including also

means for giving the knives their operative movements.

Figs. 4, 5, 6 and 7 are fragmentary longitudinal sectional elevations of the board and apparatus for cutting the same, showing my improved method for cutting plaster board.

Fig. 8 is an inside face view of the cam at one end of the bottom knife by which the knife is moved vertically in unison with its horizontal movement; and

Fig. 9 is a face view of the cam by which the knives are moved horizontally.

For the purpose of producing a strong, light weight plaster board having a plaster core made without sawdust or other similar material, it has recently been found possible to mix plaster of Paris with a greater amount of water than has heretofore been used in plaster board cores, which water is removed during the drying of the board. Consequently, the board, while passing through the machine has a softer core than plaster boards heretofore made. It has been found that cutting devices of the kind heretofore used in connection with other kinds of plaster board can not be employed without damaging this light weight board to such an extent as to affect its marketability. My invention is particularly applicable to the cutting of light weight plaster boards and does not damage the edges thereof, but I do not intend to limit the invention to such use, since the invention can be used to good advantage in cutting other kinds of plaster board or analogous materials.

A represents the board which is to be cut and which includes the usual core *a* of plastic material, the opposite faces of which are covered by means of sheets of paper *a'* or other fibrous material.

The cutting of the board is preferably effected by means of a pair of knives *B* and *C* which are normally positioned beyond opposite faces of the board and between which the board passes on its way to the discharge end of the board-forming machine. The knives shown are moved in the direction indicated by the arrows, directly toward each other, there being no movement of the knives in the direction of their length. The cutting edges of the knives are provided with a plurality of substantially V-shaped teeth *b*

and *c*, and the edge portions of these teeth are sharpened so as to effect the cutting. The two knives are preferably so arranged that the teeth of one knife will enter into the spaces between or mesh with the teeth of the other knife, and consequently during the movement of the knives toward each other, the sharp points of the V-shaped teeth will first pierce the paper or fibrous covering material of the board. Then upon further penetration into the board, the opposite sharpened edges of each tooth will extend the cuts into the covering material in opposite directions and at the same time the teeth will penetrate into the core of the board. Consequently, during the cutting stroke of the knives, first penetration of the sharpened points of the teeth through the paper or covering material will cause very little pressure to be exerted against the flat faces of the board, and during the further penetration of the teeth, considerable of the force required to cut the paper is exerted substantially in a direction parallel to the flat faces of the board, so that very little force is exerted in a direction to squeeze the soft core of the board. Consequently the knives make a clean cut in the board and leave the cut edges of the board undamaged. It has been found that the best results are obtained by having the teeth penetrate only partially through the board so that the two knives do not meet at the completion of their cutting strokes, as shown in Fig. 3, with the cutter at each face severing the paper at the corresponding face only without penetrating the paper at the opposite face.

Since the cutting of the board is effected while the board is moving continuously through the machine, my process includes the moving of the knives with the board during the cutting operation, so that during the movement of the knives toward each other to penetrate the board, the two knives move with the board and at the same rate of travel as the board, so that there is no relative movement between the knives and the board in the direction of the length of the board, as shown in Figs. 4 and 5. This movement of the knives with the board continues until the knives have completed the cutting stroke, Fig. 5, whereupon the knives are given a short movement in the same direction as the movement of the board but at a greater rate of speed. This short movement of the knives pushes the strip of board which has been cut off in advance of the remaining portion of the board, as shown in Fig. 6, and serves the two-fold purpose, in the first place of completing the separation of the two parts of the board at the point of the cut by a tearing or separating action, and furthermore forms an enlarged space between the two sections of the board through which the knives may pass in their return stroke, as shown in

Fig. 7, without contacting with either of the two cut edges of the board and without tending to separate the paper or fibrous material from the core, due to the friction between the paper and the knives.

One form of means for giving the knives their desired movement as described is shown in the drawing. Each of the knives is provided with lugs 10 at its ends slideable vertically between two spaced slide bars 11 which in turn are supported by slide blocks 12 which are slideable horizontally between two spaced slide bars 13 rigidly mounted in position. The slide blocks 12 are moved horizontally for giving the knives a corresponding movement by means of links 14 pivotally connected therewith, the forward end of the link 14 at each side of the machine being provided with a roller 15 which works in a cam 16 mounted upon a shaft 17 revolvably mounted in transverse position with respect to the machine. The cam groove in each of the cams is so shaped that when the cam is rotated in counter-clockwise direction in Fig. 9 the link is drawn at a uniform speed of 90 movement toward the right in said figure corresponding to the speed of movement of the board A until the roller 15 is brought into engagement with the portion of the cam groove indicated at 18, at which time the speed of movement of the link is quite materially increased so as to cause the knives to move considerably faster than the board. The cams 16 are connected with the shaft 17 by means of clutches 19 of any approved type which are preferably thrown into operation by means of any suitable type controlled by the forward movement of the board and automatically thrown out of operation at the end of a single complete rotation.

Upon the outer ends of the knives B and C, I have provided rollers 20 which engage in cams 21 rigidly mounted in position at opposite sides of the machine. These cam grooves are so shaped that, as the knives are moved forwardly with the board by the links 14 actuated by the cams 16, the upper knife is moved downwardly and the bottom knife is moved upwardly for operation as above described. A spring 22 is provided at the lower portion of the cam groove of the lower cam 21 for throwing the roller 20 past the critical point with respect to the return movement of the link 14 for causing the roller to continue about the groove in lieu of retracing its path. The upper cam 21 is, of course, just the reverse of the lower cam.

This method and the knives of the construction described have made possible the economic production of a light weight plaster board having a core which, while passing through the machine is softer than the cores of other plaster boards now made. Furthermore, due to their construction, the knives pass through board or other material to be

cut much more easily and with less wear on the knives than is the case with other knives or cutters heretofore used, and with less wear on the mechanism for actuating the knives.

- 5 This is probably due to the fact that the knives enter the board gradually, since at first only the points of the knives enter the surface of the board, and then due to the inclination of the cutting edges, a further 10 gradual cutting of the fibrous covering of the board results. The knives consequently make a drawing cut, rather than a shearing cut, which results in a saving of power and also enables the cutting edges of the knives 15 to remain sharp for much longer periods of time than is possible with straight edged-cutters.

I claim as my invention:

1. The hereindescribed method of cutting 20 material having a relatively soft core and relatively tough covering layers while the same is moved in the direction of its length, consisting of forcing knives in opposite directions against opposite faces of the board 25 to cut through the greater portion of the board, the knives and board travelling approximately at the same rate of speed during the penetration of the knives into the board, and completing the severing of the board by 30 moving the knives in the direction of movement of the board and at a greater speed than the movement of the board, to form an opening at the line of cut through which the knives move away from each other out of engagement with the two parts of the board. 35

2. The method of cutting sheet material 40 having a soft core interposed between layers of relatively tough material, which consists in simultaneously puncturing each layer at spaced points along the line of the proposed cut, and then cutting entirely through the layer at each face of the sheet material between said punctures by forcing therethrough the divergent cutting edges of the teeth of a 45 cutter at that face.

3. The method of cutting sheet material 50 having a soft core interposed between layers of relatively tough material, which consists in inserting the opposed edges of a pair of cutters into the opposite sides of the sheet of material so as to cut through the two layers of tough material and substantially divide the soft core, then giving the cutters a move-

ment horizontally for moving one severed portion of the sheet material edgewise away 55 from the other portion, and then moving the cutters edgewise away from each other for clearing the sheet of material.

4. The hereindescribed method of cutting 60 material having a relatively soft core and relatively tough covering layers, comprising moving the material longitudinally, forcing knives, having a plurality of V-shaped cutting edges terminating in points, against the opposite faces of the board, causing said points 65 to penetrate said covering layers, then forcing said knives to penetrate farther into said boards to exert cutting strains substantially parallel to the flat faces of the board, moving said knives during their cutting action in 70 the direction of movement of the board, and moving said knives after their cutting stroke is completed in the direction of movement of said board at a higher rate of speed than the speed of said board, to separate the cut edges 75 of the board.

5. The method of cutting a moving sheet 80 of material which comprises passing the sheet of material between opposed cutters, then moving the cutters with the sheet of material 85 and simultaneously inserting said cutters into the opposite sides of the moving sheet of material so as to divide same, then moving the severed portion away from the remainder of the sheet of material and moving the cutter edgewise of the sheet out of contact therewith, and then moving the cutters edgewise away from each other for clearing the sheet of material.

6. A cutting device of plasterboard and the 90 like, including a pair of knives movable toward each other at opposite faces of the board, each of said knives being provided with pointed teeth adapted to perforate the faces of the board and then to enlarge the 95 perforations by the action of the obliquely disposed cutting edges of the pointed teeth until the several perforations are completely united at the bases of the teeth, the points of the teeth entering either of the faces of 100 the board being still in substantial spaced relation with respect to the other face of the board after the complete severance of the face portions.
